UNITED STATES PATENT OFFICE.

STANLEY ROBERT MULLARD, OF SOUTHFIELDS, ENGLAND, ASSIGNOR TO THE MULLARD RADIO VALVE COMPANY, LIMITED, OF SOUTHFIELDS, LONDON, ENGLAND.

THERMIONIC OR OSCILLATION VALVE.

Application filed November 9, 1920. Serial No. 422,980.

To all whom it may concern:

Be it known that I, STANLEY ROBERT MULLARD, a subject of the King of Great Britain, residing at 71 Standen Road, 5 Southfields, in the county of London, England, have invented certain new and useful Improvements in or Relating to Thermionic or Oscillation Valves, of which the following is a specification.

10 This invention relates to thermionic or oscillation valves of the kind in which the bulb has a reentrant portion for supporting an electrode. The invention is particularly applicable to valves having glass bulbs but 15 it may also be applied to valves having bulbs of fused silica. The chief object of the invention is to provide improved forms of valve which permit of replacement of the electrodes and especially of the heating filament. Another object of the invention is to 20 provide improved means for supporting the electrodes and insulating them from each other.

According to one feature of this invention 25 in a valve of the kind referred to a sealing tube is attached to the reentrant portion of the bulb and extends outwards beyond the general contour of the bulb to permit of resealing.

30 In order that the above and other features of the invention may be clearly understood and readily carried into effect the same will now be fully described with reference to the accompanying drawings which show by way of example methods of carrying the invention into effect and in which:—

Figure 1 is a view partly in section of one form of valve according to this invention,

35 Figures 2 and 3 are sections on an enlarged scale on the lines 2—2 and 3—3 respectively in Figure 1,

Figures 4 and 5 are details,

Figure 6 is a view showing part of a 40 valve according to another method of carrying the invention into effect.

Referring to Figures 1 to 5, the valve comprises a bulb 1 having tubular necks 2 and 3. Within the necks 2 and 3 are reentrant parts 4 and 5 to which are sealed at 6 and 7 45 tubes 8 and 9 which extend outwards well beyond the bulb 1 and necks 2 and 3. To the outer end 10 of the tube 8 a tube 11 is sealed. Sealed into the inner end of the tube 11 are conductors 12, 12 to the inner

ends of which the filament 14 is connected. 55 The leads 15, 15 for the filament pass through the tube 11. At the other end of the valve a tube 16 is sealed at 17 within the tube 9. The inner closed end of the tube 16 is formed with a solid knob 18. A wire 60 spring 19 is formed with a hooked end 20 over which the filament 14 passes and the other end of the wire is bound around the neck 21 behind the knob 18.

The grid is formed by a wire spiral 30 65 wound on three supporting wires 31 which latter are rigidly attached to three arms 32 extending from a piece of metal 33 bent into cylindrical form (Figures 1 and 4). The part 33 is inserted within the tube 11 70 fitting the same tightly. Connection is made to the grid by a wire 34.

The plate electrode (Figures 1 and 5) is in the form of a cylinder 40 attached to three arms 41 extending from a part 42 75 (similar to the part 33 hereinbefore described) and fitting tightly within the tube 9.

It will be seen that the construction of the valve as hereinbefore described permits 80 of the filament being easily replaced owing to the sealing tubes being sealed at the points 10 and 17 which are well away from the bulb.

With the construction described all the 85 electrodes are more perfectly insulated from each other than with constructions hitherto proposed. Owing to the positions of the seals 10 and 17 extremely long leakage surfaces are provided between the filament and 90 the grid and between the filament or supporting means therefor and the plate electrode.

The invention is applicable to valves in which a sealing tube is sealed at its inner 95 end to a reentrant portion. Such an arrangement is shown in Figure 6 in which the tube 50 is sealed to a reentrant tube 51 at 52. A conductor 53 connecting to a filament is sealed in the tube 50 which extends 100 well beyond the body of the valve. The filament may be a straight one extending across the bulb.

The plate or grid electrode may be supported by arms 54 attached to a band of 105 metal 55 surrounding the reentrant tube 51.

The invention is obviously applicable to valves having only two electrodes or more

than three electrodes. The electrodes may also obviously be of other forms than those specially described above.

What I claim and desire to secure by Letters Patent of the United States is:—

1. A thermionic electric valve of the kind in which the bulb is provided with a reentrant portion for supporting an electrode and in which a sealing tube is attached to the said reentrant portion and extends outwards beyond the mouth of said reentrant portion for the purposes described.
2. A thermionic electric valve of the kind in which the bulb is provided with a reentrant portion for supporting a sealing tube carrying the filament and in which the said sealing tube extends outwards beyond the mouth of said reentrant portion for the purposes described.
3. A thermionic electric valve comprising a bulb having a reentrant tubular portion, a tubular portion within said first mentioned tubular portion and attached to the inner end thereof and a sealing tube carrying the filament attached to the outer

end of said second mentioned tubular portion.

4. A thermionic electric valve comprising a bulb having a reentrant tubular portion, a tubular portion within said first mentioned tubular portion and attached to the inner end thereof and a sealing tube attached to the outer end of said second mentioned tubular portion outside the mouth of said first mentioned tubular portion.

5. A thermionic electric valve comprising a bulb having a tubular reentrant portion, a tubular part within it joined to the inner end of said reentrant portion, a sealing tube attached to the outer end of said tubular part and an electrode supporting member comprising a cylindrical part adapted to fit tightly within said tubular part between it and the sealing tube and having a plurality of arms extending therefrom to the outer ends of which the electrode is attached.

STANLEY ROBERT MULLARD.
